UNITED STATES PATENT OFFICE.

JOSEPH A. DEDOUCH, OF OAK PARK, ILLINOIS.

CONTINUOUS CERAMIC FURNACE.

Application filed June 13, 1927. Serial No. 198,489.

This invention relates to continuous ceramic furnaces, and the like, particularly of the muffle type, and is fully described in the following specification and shown in the accompanying drawings, in which—

Figure 1 is a perspective view of an end of an embodiment of the furnace;

Figs. 2 and 3 are enlarged details of the driving mechanism;

Fig. 4 is a perspective view of an end of the furnace showing parts broken away to illustrate the furnace details;

Fig. 5, is a small perspective view of a double track furnace chamber; and

Fig. 6 is a similar view of a single track furnace.

This is an improvement on the furnace shown in my pending application for Letters Patent for continuous ceramic furnace, Serial No. 185,735, filed April 22, 1927.

The embodiment illustrated shows a furnace which may be used for enamelling, or burning, articles of considerable size and weight. In this form, the muffle furnaces 10 and 11 are placed at the two sides of the band conveyor members 12 and 13 which may be made of any suitable heat-resisting metal such as the so-called "high-speed" steel containing nickel, chromium, and the like, and which are provided with teeth on the underside throughout their lengths so that they may be positively driven at the same speeds.

The series of transversely arranged drive-shafts 14 carry bevel gears 15 which mesh with bevel gears 16, the latter being keyed on a central shaft 17 and driven by means of suitable reducing gearing from a motor 18. Shrouded gears 19 mesh with the teeth in the under portion of the band conveyors 12 and 13 while guide pulleys 20 are placed at suitable intervals to hold the band down in mesh with the gears 18.

For very heavy duty work, it may be necessary to place the shafts 14 quite close together, particularly in the furnace where the bands 12 and 13 will become quite hot while carrying the load. This construction is shown in Fig. 4 in which the furnace 10 has a muffle-chamber 21 through which passes the metal band conveyor 12, 13. Walls 22 and 23 separate the muffle-chamber from the heating-chambers 24 and 25 through which pass the hot gases of combustion.

At suitable intervals are placed transverse tubes 26 through which pass shafts 14^a which carry shrouded gears 19^a which are driven by

bevel-gears 15^a, 16^a from the central shaft 17. The gears 19^a pass through suitable openings 26^a in the tubes 26. The shafts 14^a which lie within the furnace are preferably hollow and connected by means of pipes 27 so that a suitable cooling medium, such as air, or water, may be passed through them so as to prevent them from becoming too hot. The tubes 26 are open at both ends to the atmosphere.

Referring again to Fig. 1, a suitable wire conveyor consisting of strands 28 and 29 may be used to feed the material to be burned to the conveyor and to receive it from the conveyor after it has passed through the furnace.

It will be understood in this connection that Fig. 1 shows only one end of the furnaces and that material after being burned passes from the furnace 10 at the opposite end (not shown) where it is received and disposed of, and that other material to be burned is fed to the opposite end of the furnace 11. Both of these operations may be performed by means of parallel conveyors as 28, 29, shown.

Fig. 1 shows the ends of the strands 12, 13 slidably supported upon a plate 30. If desired, idler pulleys may be provided for this purpose instead of the plate 30.

The form heretofore described is of the single track type shown in Fig. 1 while the furnace proper is shown in Fig. 5. In this furnace a burner 31 directs a jet of flame through the opening 32 which passes back through a passage 24 as shown in Fig. 4 and thence out through the pipe 33 to the stack.

Fig. 4 shows the double track arrangement having band conveyor members 34, 35 travelling in the opposite direction to the members 12 and 13. The conveyor members 34 and 35 are provided with teeth on their lower edges which mesh with shroud gears 36 on the shaft 37 which carries a bevel gear 38 which meshes with a gear 39 on the shaft 14^a which is journaled in suitable bearings (not shown). The conveyor members 34 and 35 may also be provided at their ends and at intermediate points with means for driving similar to those shown and described in connection with the drive for the conveyor members 12 and 13 except that they are driven in the reverse direction.

Fig. 6 shows a furnace chamber 10^a which is heated by means of a gas or oil burner 40 which delivers through an opening 41 in the side of the furnace. The gases then spread and go toward both ends of the furnace where

they pass out of the pipes 42 and 43 which connect with a suitable flue or stack.

One of the advantages of this double track furnace is that the hottest part of the fur-

6 nace is at or near the center and that the work to be fired increases in temperature until shortly after it has passed the center of the furnace after which it is hotter than the incoming work on the adjacent track or conveyor. Consequently the objects which have just been fired give up part of their heat to the incoming work and the incoming objects on the adjacent conveyor. This ensures a more efficient heating with a consequent sav-
10 ing of fuel and at the same time causes the incoming work to be heated more rapidly than would otherwise be the case.

Thus it will be seen that a very simple and efficient form of furnace is provided and one 20 which is capable of being modified to adapt it for a wide range of uses.

While I have shown and described but a few embodiments of my invention, it is to be understood that it is capable of many modifications. Changes, therefore, in the arrangement and construction may be made which do not depart from the spirit and scope of the invention as disclosed in the appended claims in which my intention is to 30 claim the invention as broadly as possible, in view of the prior art.

I claim:

1. In combination, a ceramic furnace having a horizontal heating chamber, continuous 35 integral parallel conveyor elements passing through said chamber, and means in said chamber for supporting and propelling said conveyor elements.

2. In combination, a ceramic furnace having a horizontal heating chamber, continuous 40 parallel conveyor elements passing through said chamber, gear teeth on the bottom of said conveyor elements, and gears in said heating chamber adapted to mesh with said gear teeth to propel said conveyor elements through said chamber.

3. In combination, a ceramic furnace having a horizontal heating chamber, continuous 50 parallel conveyor elements passing through said chamber, said elements being flat and having teeth formed on their lower edges, and gears meshing with said teeth for propelling said conveyor elements.

4. In combination, a ceramic furnace having a horizontal heating chamber, continuous 55 parallel conveyor elements passing through said chamber, said elements being flat and having teeth formed on their lower edges, and gears in said chamber meshing with said teeth for propelling said conveyor elements.

5. In combination, a ceramic furnace having a horizontal heating chamber, continuous 65 parallel conveyor elements passing through said chamber, said elements being flat and

having teeth formed on their lower edges, and gears arranged in pairs on the same shaft meshing with said teeth for propelling said conveyor elements.

6. In combination, a ceramic furnace hav- 70 ing a horizontal heating chamber, continuous parallel conveyor elements passing through said chamber, said elements being flat and having teeth formed on their lower edges, and gears with shrouded sides for guiding 75 and meshing with said teeth for propelling said conveyor elements.

7. In combination, a ceramic furnace hav- 80 ing a horizontal heating chamber, continuous parallel conveyor elements passing through said chamber, gear teeth on the bottom of said conveyor elements, gears in said heating chamber adapted to mesh with said gear teeth to propel said conveyor elements through 85 said chamber, and means for cooling said gears.

8. In combination, a ceramic furnace hav- 90 ing a horizontal heating chamber, continuous parallel conveyor elements passing through said chamber, gear teeth on the bottom of 95 said conveyor elements, gears in said heating chamber adapted to mesh with said gear teeth to propel said conveyor elements through said chamber, said gears being carried on hollow shafts, and means for passing cool- 100 ing fluid through said hollow shafts.

9. In combination, a ceramic furnace hav- 100 ing a horizontal heating chamber, continuous parallel conveyor elements passing through said chamber, said elements being flat and having gear teeth on the lower edge, gears at intervals throughout the straight portions of 105 said element for propelling the same, and a common means for driving all said gears.

10. In combination, a ceramic furnace hav- 110 ing a horizontal heating chamber, continuous parallel conveyor elements passing through said chamber, said elements being flat and having gear teeth on the lower edge, gears at intervals throughout the straight portions of 115 said element for propelling the same, and a longitudinally disposed shaft for driving all said gears.

11. In combination, a ceramic furnace hav- 120 ing a horizontal heating chamber, continuous parallel conveyor elements passing through said chamber, said elements being bands, means for maintaining said elements in an upright position, and means in said chamber for propelling said conveyor elements.

12. In combination, a ceramic furnace hav- 125 ing a horizontal heating chamber, continuous parallel conveyor elements passing through said chamber, said elements being bands, means for maintaining said elements in an upright position, means for supporting said elements on the return bends, and means in said chamber for propelling said conveyor elements.

13. In combination, a ceramic furnace hav-

ing two furnace chambers arranged side by side, continuous integral parallel conveyor elements passing through said furnaces, and means for propelling said elements.

5 14. In combination, a ceramic furnace having a horizontal heating chamber, continuous parallel conveyor elements passing through said chamber, means in said chamber for propelling said conveyor elements, and a second 10 conveyor for delivering to said conveyor elements and receiving therefrom objects to be fired.

15 15. In combination, a ceramic furnace chamber, means for heating the same, integral parallel conveyor members adapted to carry objects to be heated in opposite directions therethrough so that the heat of the objects emerging from the furnace will be utilized to raise the temperature of adjacent in- 20 going objects.

16. In combination, a ceramic furnace having a horizontal heating chamber, continuous integral parallel conveyor elements passing through said chamber, means in said chamber 25 for propelling said conveyor elements, and means for cooling said propelling means.

17. In combination, a ceramic furnace having a horizontal heating chamber, continuous parallel conveyor elements passing through 30 said chamber, said elements being flat and having teeth formed on their lower edges, gears meshing with said teeth for propelling said conveyor elements, shafts carrying said gears, and means for cooling said shafts.

35 18. In combination, a ceramic furnace hav-

ing a horizontal heating chamber, continuous parallel conveyor elements passing through said chamber, said elements being flat and having teeth formed on their lower edges, gears meshing with said teeth for propelling 40 said conveyor elements, shafts carrying said gears, and water-cooling means for cooling said shafts.

19. In combination, a ceramic furnace having a horizontal heating chamber, continuous 45 integral parallel conveyor elements passing through said chamber, means in said chamber for propelling said conveyor elements, and a chamber separate from the heating chamber for enclosing said propelling means. 50

20. In combination, a ceramic furnace having a muffle chamber, a heating chamber separated therefrom, continuous parallel conveyor elements passing through said muffle chamber, means for propelling said conveyor elements, and a chamber lying between said muffle and heating chambers and enclosing 55 the driving means.

21. In combination, a ceramic furnace having a horizontal heating chamber, continuous 60 parallel conveyor elements passing through said chamber, said elements being flat and having teeth formed on their lower edges, and gears meshing with said teeth for propelling said conveyor elements, said gears having 65 flanges to guide said elements.

In testimony whereof, I have hereunto set my hand and seal this 31st day of May A. D. 1927.

JOSEPH A. DEDOUCH.
